UNITED STATES PATENT OFFICE.

MAX STERN, OF ELBERFELD, GERMANY, ASSIGNOR TO FARBENFABRIKEN VORM.
FRIEDR. BAYER & CO., OF ELBERFELD, GERMANY, A CORPORATION OF GERMANY.

CHOLESTERIN PREPARATION.

1,034,161.

Specification of Letters Patent. Patented July 30, 1912.

No Drawing.

Application filed May 17, 1911. Serial No. 627,812.

To all whom it may concern:

Be it known that I, MAX STERN, doctor of philosophy, chemist, citizen of the German Empire, residing at Elberfeld, Germany, have invented new and useful Improvements 5 in Cholesterin Preparations, of which the following is a specification.

I have found that new therapeutical compounds can be obtained by mixing esters of 10 higher fatty acids with esters of cholesterin. The mixtures thus obtained possess a low melting point (below blood-heat) and when they are once melted remain in the molten state at the ordinary temperature. It is 15 thus possible to cause the assimilation by the human body of cholesterin by administration either internally or by subcutaneous injection without using too much of indifferent substances.

20 A mixture of 2 parts of the oleic ester of cholesterin and 1 part of the ethylic ester of oleic acid melts at 29° C., the mixture with the methylic ester of palmitic acid melts at 31° C. while the pure cholesterin ester melts at 40-45° C. and is not suitable 25 for subcutaneous injections. Olive oil or phenylpalmitate, etc., can also be used.

I claim:—

1. The herein described therapeutical composition comprising in intermixture esters 30 of higher fatty acids and esters of cholesterin, which possess a low melting point and remain in a molten state at body temperatures and for some time even at ordinary temperatures when once melted, and 35 which are suitable for either internal assimilation or subcutaneous injection, substantially as described.
2. The herein described therapeutical compositions comprising the oleic ester of cholesterin and an ester of a higher fatty acid. 40
3. The herein described therapeutical compositions comprising the oleic ester of cholesterin and an ester of oleic acid, substantially 45 as described.

In testimony whereof I have hereunto set my hand in the presence of two subscribing witnesses.

MAX STERN. [L.S.]

Witnesses:

CHAS. J. WRIGHT,
ALFRED HENKEL.
